Primary Examiner — Mark Goodwin(74) *Attorney, Agent, or Firm* — Nelson Mullins Riley & Scarborough LLP(57) **CLAIM**

The ornamental design for a bagging blade, as shown and described.

DESCRIPTION

FIG. 1 is a top perspective view of a bagging blade in accordance with an embodiment of the present invention; FIG. 2 is a bottom perspective view of the bagging blade of FIG. 1;

FIG. 3 is a top view of the bagging blade of FIG. 1; FIG. 4 is a bottom view of the bagging blade of FIG. 1; FIG. 5 is a front side view of the bagging blade of FIG. 1; FIG. 6 is a back side view of the bagging blade of FIG. 1; FIG. 7 is a right side view of the bagging blade of FIG. 1; and,

FIG. 8 is a left view of the bagging blade of FIG. 1. The broken lines of FIGS. 1-8 are illustrative of the visible environmental structure of the bagging blade and form no part of the claimed design.
